UNITED STATES PATENT OFFICE.

ORA MASON, OF SANDOVAL, ILLINOIS.

BARBEE'S APRON.

Application filed September 1, 1928. Serial No. 303,509.

This invention relates to an improved type of neck band designed particularly for use upon barbers' aprons, or other aprons of this character where a neck opening is formed to 5 permit the apron to hang over and cover the shoulders of the person using the same. In aprons of the type at present in use, the neck bands are secured in place usually by pins and it frequently happens that the person about 10 whose neck the band is being secured is injured when the band is being placed in position or they are subjected to extreme discomfort by reason of the fact that the band is drawn and pinned too tight. An important 15 object of the present invention is to overcome the foregoing difficulties by providing a neck band of an improved character whereby no pins or other fastening means of this character are employed and while the band 20 will be held securely in place, there will be sufficient give to prevent any uncomfortable binding of the band.

The invention broadly contemplates the provision of a band having a series of buttons 25 at each end and upon the outer face thereof and secured to the band intermediate its ends is a pair of tapes. When the band is placed in position, one end is located over the back of the neck after which the other end is 30 brought into overlapping relation thereto so that its upper edge will engage under the buttons of the underlying end.

The ends of the tapes are then drawn about the neck over the band and tied with 35 the upper edge of one of the same engaging under the buttons of the outer end of the neck band.

A further object of the invention is to provide means whereby the neck band of an 40 apron of the character described may be quickly and easily placed in position without the employment of fastening elements other than those forming a part of the band structure.

45 The invention will be best understood from a consideration of the following detailed description taken in connection with the accompanying drawings forming part of this specification, with the understanding, however, that the invention is not confined to any strict conformity with the showing of the drawings but may be changed or modified so long as such changes or modifications mark no material departure from the salient features of the invention as expressed in the appended claims.

In the drawing:—

Figure 1 is a perspective view of the upper portion of the barber's apron carrying the improved neck band embodying the present 60 invention;

Figure 2 is a view of the outer face of the collar band in opened out condition.

Referring to the drawing, the numeral 1 indicates generally an apron of the type used 65 by barbers or hair dressers, the same being open and designed to be hung loosely over the customer's shoulders.

About the edge of the neck opening of the apron is secured the improved neck band embodying the present invention, this band being indicated as a whole by the numeral 2.

70 It is intended that the present collar band be made up for application to the neck openings of aprons the same as those bands used upon shirts, the lower edge of the band being stitched to the edge of the apron neck opening along its lower edge as indicated at 3.

75 At each end, the band has secured thereto upon the outer face, a series of buttons 4. 80 These buttons are secured adjacent the top edge of the band so that a portion thereof will project above the upper edge of the band in the manner shown. Secured to the face of the band intermediate its ends, as at 5, 85 is a tie-up tape indicated as a whole by the numeral 6, this tape being attached intermediate its ends, thus providing the free portions or strings 7.

90 When the apron carrying the present improved band structure is placed in position about the shoulders of a customer the neck band is secured by first bringing one end to position across the back of the customer's neck, as for example, the left hand end, after 95 which the other end is brought into overlapping relation thereto with its top edge engaging under the buttons of the underlying end. After thus positioning the band ends the strings 7 of the tape 6 are drawn about the 100 neck band and tied together, the top edge of one of the strings engaging under the buttons of the outer neck band end in the manner shown.

105 From the foregoing description taken in connection with the drawing, it will be seen that there will be interlocking relation set up between the buttons and the collar band ends and tape, the band being prevented from slipping downwardly from under the tape by the 110 buttons which, when any downward pull is exerted upon the apron, will be tipped in-

wardly toward the neck of the customer to bear thereagainst. It will also be seen that while the connection made between the band ends will be secure and will be sufficiently tight to prevent hair or water from going down the customer's neck, it will not be so tight as to be uncomfortable as there will be sufficient give to prevent this condition.

Having thus described my invention what I claim is:—

- 10 1. A neck band structure of the character described, comprising a band body, buttons carried upon each end and upon the outer face of the body, said ends being designed to be engaged in overlapping relation with the upper edge of one end engaging under the buttons of the other end, and means extending over the overlapped ends of the band for holding the same in position.
- 15 2. A collar band of the character described, comprising a band body, button members arranged in spaced relation upon the outer face of the body adjacent each end thereof, one end

of the band body being designed to overlap the other end and to have its top edge engaged under the buttons of the underlying end, and means carried by the band and designed to be secured over the overlapping ends and to engage beneath the buttons of the outer end to hold the ends in position.

3. A collar band comprising a band body, a plurality of buttons arranged in spaced relation upon the outer face of the body adjacent each end, said buttons being arranged to project above the top edge of the band, one end of the band being designed to overlap the other end with its upper edge engaging under the buttons of the overlapped end, and tie strings secured to the band and designed to be drawn thereabout and tied, with the upper edge of one thereof engaging beneath the buttons of the outer end of the band.

In testimony whereof I hereunto affix my signature.

ORA MASON.
